UNITED STATES PATENT OFFICE.

HARVEY HOGAN, OF ROCKFORD, ILLINOIS, ASSIGNOR TO M. I. MORLEY, OF ROCKFORD, ILLINOIS.

LADDER.

1,305,107.

Specification of Letters Patent. Patented May 27, 1919.

Application filed February 21, 1918. Serial No. 218,523.

To all whom it may concern:

Be it known that I, HARVEY HOGAN, a citizen of the United States, residing at Rockford, in the county of Winnebago and State of Illinois, have invented certain new and useful Improvements in Ladders; and I do hereby declare the following to be a full, clear, and exact description of the invention, such as will enable others skilled in the art to which it appertains to make and use the same.

The present invention relates to improvements in ladders, and has for an object to provide a ladder adapted more particularly for the use of tree trimmers; and to this end the invention has for an object to provide a single stile foldable ladder having means to secure it in the folded condition and a handle whereby it may be readily transported from place to place.

Another object of the present invention resides in providing a ladder with a hook by which it may be suspended above the ground, and with a rest which is adapted to support the ladder when resting on the ground, while also providing a first step for the ladder in the elevated position.

The invention also aims to provide an improved connecting joint between the hinged sections of the ladder stile and improved steps made up of single lengths of strap metal.

In the accompanying drawings forming a part of this application, and in which similar reference symbols indicate corresponding parts in the several views:

Figure 1 is a perspective view of one form of a ladder constructed in accordance with my invention.

Fig. 2 is a plan view of the ladder in the folded position; and

Fig. 3 is a fragmentary sectional view showing the connection between the stile sections of the ladder.

Referring more particularly to the drawings, 1 designates an upper and 2 a lower section of the single stile of the ladder. The leaf 3 of a hinge is secured to the upper section 1, while the leaf 4 of the same hinge is fastened to the adjacent end of the lower section 2. The hinge provides for folding the sections 1 and 2 as shown in Fig. 2, in which position they are securely held together by a strap 5 through which they are

passed; and the ladder in such folded condition is adapted to be readily and conveniently transported by means of the handle 6 attached at a convenient point to one of the stile sections.

A brace 7 is held by a bolt 8 on the end 60 of the stile section 1, such brace extending beyond such end and being adapted to lie in contact with the adjacent side of the stile section 2 to which it is connected by a bolt 9 having a winged nut 10 for convenience in 65 removing and replacing.

Side members 11 are formed in the same piece with the brace 7 and extend at right angles thereto and close against the corresponding faces of the sections 1 and 2. 70 Bolts 12 may be used to connect these members to the section 1.

At the bottom of the lower section 2 of the stile I provide a rest consisting of a looped strip or length of strap iron, or other 75 suitable material, having side supporting arms 13 and a ground engaging and thread portion 14. The arms 13 are secured as by the bolts 15 to the stile. The rest provides a means whereby the ladder is supported on 80 the ground and it supplies the further function of forming a first step when the ladder is suspended at an elevation above the ground as, for instance, when the hook 16 at the top of the ladder is engaged with the 85 bough of a tree, in which case the ladder becomes a scaling ladder.

Steps are provided at opposite sides of the ladder stile, as clearly shown in Fig. 1, the successive steps alternating on opposite 90 sides and preferably composed of single lengths of strap metal having horizontal treads 17 projecting at right angles from the face of the stile to which they are secured, and being supported by braces 18 bent from the outer ends thereof and returned diagonally to the stile. The terminal ends 19 and 20 of the treads 17 and diagonal braces 18 are bent over and perforated to receive fastening means 21 by which they are secured 100 to the ladder in the appropriate position.

I also preferably provide the ladder with a guard 22 at the upper end of the stile, and in the instance shown in the drawings the guard is advantageously formed of a 105 single piece of metal perforated centrally for the passage of a bolt 21 by which it is secured in place, and being curved to con-

form to the curvature of a tree trunk in order to hold the ladder against lateral motion.

In use the ladder is placed in the condition shown in Fig. 1, with the bolt 9 engaged through the brace 7, and the ladder is either supported from the ground by the rest 14 or from an object above by the hook 16.

In the latter case the rest 14 will be supported at an elevation above the ground and will constitute the first step of the ladder.

When the ladder is to be transported, the winged nut 10 may be removed from the bolt 9 and the sections 1 and 2 folded about the hinge 3, 4, so that the sections lie parallel, as indicated in Fig. 2. The strap 5 is then passed about said sections to secure them together, and the handle 6 may be grasped and the ladder lifted and transported. The strap 5 is also useful in holding the stile at any point to an object to which it is applied to prevent swaying of the ladder.

It is obvious that those skilled in the art may vary the details of construction and arrangements of parts without departing from the spirit of my invention, and therefore I do not wish to be limited to such features except as may be required by the claims.

I claim:

1. A ladder of the character described including a stile composed of upper and

lower sections, a hinge connecting said upper and lower sections whereby same may be folded together, a looped rest carried at the lower end of said lower section and projecting beyond the sides thereof, a guard fastened to the upper end of said upper stile section and projecting beyond opposite sides of said section, said rest and guard adapted to be brought close together when the two sections are folded, and a hook secured to the upper end of said upper section, substantially as described.

2. An improved ladder including two stile sections placed side by side, a hinge connecting said sections whereby the same may be swung apart, steps carried by said stile sections, a looped rest providing a tread carried by the lower section at the lower end thereof, a guard secured to the upper end of the upper stile section and projecting to opposite sides thereof, said rest and guard being disposed close together when the sections are folded, a hook carried by the upper section and projecting upwardly therebeyond, said hook having its pointed bill arranged close to said rest when the sections are folded, a handle fixed to one of said sections, and means passing about both of the sections and through said handle whereby the sections may be secured together, substantially as described.

In testimony whereof, I affix my signature.

HARVEY HOGAN.
